UNITED STATES PATENT OFFICE

2,672,620

PATIENT HANDLING DEVICE FOR
BATHTUBS

John N. Gross, San Diego, Calif., assignor of one-half to Dewey C. Rickenbacker, Beverly Hills, Calif.

Application February 11, 1952, Serial No. 271,007

6 Claims. (CL 4-185)

1

My invention relates to a patient handling device for bathtubs and the objects of my invention are:

First, to provide a patient handling device for bathtubs which is adapted to gently place patients in a bathtub and remove patients therefrom whereby manual effort normally required to handle such patients is substantially eliminated.

Second, to provide a patient handling device for bathtubs which may be readily inserted in conventional bathtubs without any attachment or mechanical connection therewith for supporting the device in the bathtub.

Third, to provide a patient handling device for bathtubs having a frame which engages the inner side of a bathtub on which patient elevating mechanism is secured whereby said device may be installed and ready for use within a bathtub by simply placing the same therein.

Fourth, to provide a patient handling device of this class which is very compact and neat in proportion to its utility.

Fifth, to provide a patient handling device of this class which is readily removably inserted in bathtubs whereby it may be very easily cleaned and sterilized.

Sixth, to provide a device of this class which is very light permitting it to be easily handled by the nurses or other hospital attendants.

Seventh, to provide a patient handling device of this class having elevating arms provided with novel lateral extensions parallel to the pivotal axis of said arms permitting the patient supporting tray to be moved laterally over the edge of the bathtub in order to transfer a disabled patient from said handling device to a portable cot without appreciable manual effort.

Eighth, to provide a patient handling device of this class having novel compact driving means which is enclosed in a housing fixed to the frame which is removably insertable in a conventional bathtub whereby the complete device including the elevating mechanism and the driving mechanism is a unitary readily portable device and

Ninth, to provide a patient handling device for bathtubs which is simple and economical of construction, efficient in operation and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference

2

being had to the accompanying drawings and to the characters of reference thereon forming a part of this application in which:

Figure 1 is a fragmentary top or plan view of a bathtub showing my patient handling device therein and showing portions broken away and in section to amplify the illustration.

Figure 2 is a side elevational view of a bathtub having my patient handling device therein showing portions of the bathtub and the device broken away and in section to facilitate and amplify the illustration.

Figure 3 is a transverse sectional view taken from the line 3-3 of Figure 2 showing by dash lines a partially elevated position of the elevating mechanism of my patient handling device and illustrating lateral extension of the patient supporting tray beyond the edge of the bathtub.

Similar characters of reference refer to similar parts and portions throughout the several views of the drawings.

The tub 1, elevator frame 2, arms 3, 4, 5 and 6, shafts 7 and 8, tray extension supports or reduced rods 9 and 10, retainers 11 and 12, tray 13, gears 14, 15, 16 and 17, main shaft 18, motor 19, and the casing 20 constitute the principal parts and portions of my patient holding device for bathtubs.

The bathtub 1 is a conventional bathtub which may be of any desired form. The elevator frame 2 is provided with a pair of substantially transversely extending U-shaped members 2a interconnected by a longitudinal frame member 2b as shown best in Figs. 2 and 3 of the drawings. The vertical frame members 2a as shown in Fig. 2 of the drawings hereinbefore referred to as U-shaped in cross section frame members are interconnected at their upper ends with the casing 20 on one side and by means of the longitudinal frame member 2c on the opposite side thereof as shown best in Fig. 1 of the drawings. The shafts 7 and 8 are rotatably mounted in the casing 20 and adjacent upright portions 2a of the frame 2 and fixed on these shafts 7 and 8 are the gears 14 and 15. On the opposite ends of the shafts 7 and 8 are the arms 4 and 6 respectively which are integrally connected with the arms 3 and 5 respectively pivotally mounted on the trunnions 2d and 2e fixed to the upright portions 2a of the frame 2. These trunnions 2d and 2e extend inwardly in axial alignment with the shafts 7 and 8 respectively and are substantially flush with the inner sides of the arms 3 and 5. The integral cross members 4a and 6a are hollow tubular members in which the tray extension

supports or reduced rods 9 and 10 are reciprocally slidably mounted. These tray extension supports 9 and 10 are retained in the hollow tubular members 4a and 6a by means of the retainers 11 and 12 which are pivoted spring clip members mounted on the arms 4 and 6 as shown best in Figs. 1 and 2 of the drawings. It will be here noted that the hollow tubular members 4a and 6a are fixed to the arms 3 and 5 providing unitary movement of the arms 3 and 5 with the arms 4 and 6. 10 These members 4a and 6a provide a support for the tray 13. This tray 13 is provided with notched bearing portions 13a and 13b which notched bearing portions engage the hollow tubular members 6a and 4d respectively. The shaft 18 is mounted in the casing 20 by means of the bearings 18a and fixed on this shaft 18 are the worm gears 16 and 17 meshing with the gears 14 and 15 respectively. The motor 19 is a reduction gear motor coupled with the shaft 18 for driving the same. The casing 20 encloses the driving mechanism for my patient handling device for bath tubs and the entire structure thereof, including the elevating means hereinbefore described, is connected to the frame 2 which is readily removably inserted in a conventional bath tub.

The operation of my patient handling device for bath tubs is substantially as follows:

When it is desired to lower a disabled patient into the bath tub 1, the conventional portable cot is rolled into position adjacent the bath tub 1 and the motor 19 is energized which rotates the shaft 18 turning the gears 16 and 17 in mesh with the gears 14 and 15 respectively causing rotation of the shaft 7 and 8 which pivots the arms 4 and 6 and 3 and 5 respectively elevating the tray on the hollow tubular members 4a and 6a to a position substantially on a level with the upper surface of the portable cot on which the disabled patient is located, all as indicated by dash lines in Fig. 3 of the drawings. When the arms 3, 4, 5 and 6 are in such elevated position the tray extension supports 9 and 10 are released by pivoting the retainers 11 and 12 to the dash line positions as shown in Fig. 2 of the drawings permitting these extension supports to be axially slid outwardly of the tubular members 4a and 6a to the extended dash line position beyond the side of the bath tub whereupon the tray 13 is supported beyond the side of the bath tub in close proximity with the portable cot on which the disabled patient is located. The patient is rolled off the tray 13 which is then retracted to a position over the bath tub 1 by slidably retracting the tray extension supports 9 and 10 and latching them into position by means of the retainers 11 and 12. The motor 19 is then energized which causes reverse rotation of the shaft 18 together with the shaft 7 and 8 which gently lowers the tray 13 into the bottom of the bath tub 1 and immerses the disabled patient in the bath.

It will be here noted that a conventional electrical circuit and suitable limit switches may be provided for the purpose of stopping the pivotal movement of the arms 3, 4, 5 and 6 at the desired locations to correspond with certain requirements.

Though I have shown and described a particular construction, combination, and arrangement of parts and portions, I do not wish to be limited to this particular construction, combination and arrangement but desire to include in the scope of my invention, the construction, com-

bination and arrangement substantially as set forth in the appended claims.

Having thus described my invention, what I claim as new and desire to secure by Letters Pat-

- 5 1. In a patient handling device for bath tubs, a frame adapted to be removably inserted in a bath tub, trunnions on said frame, a pair of arms pivoted on said trunnions at each side of said frame, hollow tubular members interconnecting said arms, a tray positioned over said hollow tubular members, means for driving said arms for raising and lowering said tray, and means 10 slidably mounted in said hollow tubular members being extendable laterally of said frame when said arms are elevated for supporting said tray beyond one side of said frame.

15 2. In a patient handling device for bath tubs, a frame adapted to be removably inserted in a bath tub, trunnions on said frame, a pair of arms pivoted on said trunnions at each side of said frame, hollow tubular members interconnecting said arms, a tray positioned over said hollow tubular members, means for driving said arms for raising and lowering said tray, means 20 slidably mounted in said hollow tubular members being extendable laterally of said frame when said arms are elevated for supporting said tray beyond one side of said frame, said driving means comprising a shaft adjacent the side of and supported on said frame and having gear means connected to said shaft for driving said arms, and a motor for operating said shaft.

25 3. In a patient handling device for bath tubs, a frame removably insertable into a bath tub, arms pivotally mounted in said frame, hollow tubular rods connected to and between said arms, reduced diameter rods slidably mounted within said hollow rods and releasable latches connected to certain of said arms and abutting said reduced rods, a tray mounted on said hollow rods and 30 slidably relative thereto to provide for lateral extension of said tray and said reduced rods relative to said frame and said hollow rods when the arms are elevated to extend above the bath tub, and means for pivoting said arms for raising and lowering said tray.

35 4. In a patient handling device for bath tubs, a frame removably inserted in a bath tub, a shaft secured to one side of said frame, a motor operatively connected to said shaft, worm gears spaced apart on said shaft, pinion gears on said frame driven by said worm gears, arms pivotally secured to and actuated by said pinion gears, a table pivotally secured to said arms whereby 40 said table is raised and lowered relative to said frame for placement and removal of said patient relative to a bath tub when said motor is energized.

45 5. In a patient handling device for bath tubs, a frame removably inserted in a bath tub, a shaft secured to one side of said frame, a motor operatively connected to said shaft, worm gears spaced apart longitudinally on said shaft, pinion gears pivoted on said frame and driven by said worm 50 gears, a first pair of arms secured to and raised and lowered by said pinion gears, a second pair of arms pivotally secured to said frame and being transversely opposite from said first pair of arms, hollow tubular rods transversely arranged relative to said frame and connecting said first and second pairs of arms, reduced diameter rods slidably mounted within said hollow tubular rods, 55 releasable latches abutting said reduced diameter rods and secured to said first pair of arms, a table supported by said hollow tubular rods, whereby 60 said table is raised and lowered relative to said frame for placement and removal of said patient relative to a bath tub when said motor is energized.

65 6. In a patient handling device for bath tubs, a frame removably inserted in a bath tub, a shaft secured to one side of said frame, a motor operatively connected to said shaft, worm gears spaced apart longitudinally on said shaft, pinion gears pivoted on said frame and driven by said worm 65 gears, a first pair of arms secured to and raised and lowered by said pinion gears, a second pair of arms pivotally secured to said frame and being transversely opposite from said first pair of arms, hollow tubular rods transversely arranged relative to said frame and connecting said first and second pairs of arms, reduced diameter rods slidably mounted within said hollow tubular rods, 70 releasable latches abutting said reduced diameter rods and secured to said first pair of arms, a table supported by said hollow tubular rods, whereby 75 said table is raised and lowered relative to said frame for placement and removal of said patient relative to a bath tub when said motor is energized.

said latches may be released and when said arms are elevated to extend above the bath tub said table may be moved transversely relative to said frame and supported on said reduced diameter rods extending laterally relative to said hollow tubular rods.

6. In a patient handling device for bath tubs, a frame removably insertable in a bath tub, pairs of arms pivotally secured in transversely opposing relation on the sides of said frame, horizontal members rigidly secured to said arms and extending between the arms of each pair of arms, said members mounting supports longitudinally extensible axially of said members when the arms are elevated above the level of the bath tub, a 15 tray mounted on said horizontal members and slidably with and supported by said extensible

5

supports for patient loading and unloading at the side of a bath tub wherein the device is mounted, and means for pivotally moving said arms for raising and lowering the tray relative to said frame.
